(57) **CLAIM**

The ornamental design for a pillar for vacuum insulated glass unit, as shown and described.

DESCRIPTION

FIG. 1 is a perspective view of the new design for a pillar for vacuum insulated glass unit;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the pillar in use between two panes of glass in a portion of a vacuum insulated glass unit.

Broken lines are used to show a portion of a vacuum insulated glass unit that forms no part of the claimed design.
